TELEVISION RECEIVER

William R. Aiken, Los Altos, Calif., assignor by mesne assignments, to Kaiser Aircraft & Electronics Corporation, a corporation of New York

Application January 21, 1955, Serial No. 34,118

Term of patent 14 years

(Cl. D56—4)

FIG. 1.

FIG. 2.

FIG. 4.

FIG. 3.

The dominant features of my design reside in the portions shown in full lines and the bottom surface, not shown, is substantially plain.

I claim:

The ornamental design for a television receiver, substantially as shown and described.
